ELECTRIC DRILL

Max J. Demo, Julian, Calif.

Application April 14, 1941, Serial No. 388,445

14 Claims. (Cl. 255—47)

My invention relates to an electric drill, more particularly an electric drill in which the tool operating shaft reciprocates and rotates while being fed outwardly of the drill land the objects of my invention are:

First, to provide an electric drill of this class in which the hammer member, the tool operating shaft and the feed screw all operate on a common axis;

Second, to provide an electric drill of this class in which water or air is passed through the feed screw thereof in concentric relation with the tool operating shaft of my electric drill;

Third, to provide an electric drill of this class in which rotation, reciprocation and outward shifting of the tool operating shaft is accomplished by means operating on a common axis providing compact relation of the operating mechanism of my electric drill;

Fourth, to provide an electric drill of this class in which a water and air pump is positioned and arranged to supply water and air under pressure to the tool in connection with my electric drill providing an arrangement whereby auxiliary pumps are not needed to operate my electric drill;

Fifth, to provide an electric drill of this class which is entirely operated by electric power delivered directly to my electric drill only;

Sixth, to provide an electric drill of this class in which the hammer members act upon a tool operating shaft clutch which is so arranged that it frictionally engages the tool operating shaft and imparts hammer action thereto when said tool operating shaft is feeding outwardly of said clutch and rotating at the same time;

Seventh, to provide an electric drill of this class which is very efficient, easy to operate, relatively light and admirably adapted for use in various drilling operations executed in confined positions;

Eighth, to provide an electric drill of this class in which automatic trip means stops the rotative operation of the feed screw when it arrives at the limit of travel in either direction;

Ninth, to provide an electric drill of this class which may be used only as a rotational drill or as both a rotational and hammer drill;

Tenth, to provide an electric drill of this class in which a pump is enclosed and arranged for use as a common means in supplying water or air to the tool in connection with my electric drill;

Eleventh, to provide a novel electric drill of this class;

Twelfth, to provide an electric drill of this class in which a light is provided for use in illuminating dark places in which my electric drill is used;

5 Thirteenth, to provide an electric drill of this class in which outwardly extending portions of the tool operating shaft are covered when passing inwardly and outwardly of my electric drill;

Fourteenth, to provide an electric drill of this class in which substantially all the operating mechanism is enclosed preventing breakage of the same; and

10 Fifteenth, to provide an electric drill of this class which is very simple and economical of construction in proportion to its utility, efficient in its action and which will not readily deteriorate and get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a fragmentary longitudinal sectional view of my electric drill taken from the line 1—1 of Fig. 2 showing parts and portions in elevation to facilitate the illustration; Fig. 2 is a transverse sectional view taken from the line 2—2 of Fig. 1; Fig. 3 is an enlarged fragmentary sectional view of one end of my electric drill taken from the line 3—3 of Fig. 5 showing parts and portions in elevation to facilitate the illustration; Fig. 4 is an enlarged fragmentary sectional view of the opposite end of my electric drill taken on substantially the same plane as Fig. 3 showing parts and portions in elevation to facilitate the illustration and also showing by dash lines varying positions of parts and portions; Fig. 5 is a transverse sectional view taken from the line 5—5 of Fig. 4; Fig. 6 is a fragmentary sectional view taken from the line 6—6 of Fig. 4 showing portions broken away to facilitate the illustration; Fig. 7 is a fragmentary sectional view taken from the line 7—7 of Fig. 3; Fig. 8 is a reduced detail sectional view of the cam member of my electric drill taken from the line 8—8 of Fig. 7; Fig. 9 is a reduced sectional view of the cam member of my electric drill taken from the line 9—9 of Fig. 7 showing the opposite side of the cam member from that shown in Fig. 8; Fig. 10 is a plan sectional view taken from the line 10—10 of Fig. 4, and Fig. 11

is a fragmentary sectional view taken from the line 11—11 of Fig. 10.

Similar characters of reference refer to similar parts and portions throughout the several views of the drawings:

The casing members 1, 2, 3, 4, 5 and 6, journal members 7, 8, 9, 10 and 11, rotor 12, rotor shaft 13, tool operating shaft 14, feed screw 15, feed screw engaging nut 16, feed screw swivel connection 17, gears 18, 19, 20, 21, 22, 23 and 24, gear shaft 25, gear operating clutch members 26, 27, 28 and 29, clutch operating trip levers 30 and 31, pump 32, pump inlet conductor 33, pump outlet conductor 34, pump inlet valve 35, valve operating lever 36, valve operating link 37, water inlet conductor 38, air inlet conductor 39, air cleaner 40, fan 41, armature brushes 42, motor field 43, hammer members 44 and 45, hammer operating spring 46, hammer operating cam 47, tool operating shaft clutch 48, clutch operating lever 49, clutch control link 50, clutch control ring 51, tool operating shaft cover 52, slip ring 53, main control levers 54 and 55 and the light bulb 56 constitute the principal parts and portions of my electric drill.

The casing member 1 is arranged to partially enclose the front end of my electric drill and it is provided with an opening 1a therein through which extends the tool operating shaft 14 together with the tool operating shaft cover 52. Positioned in the front upper side of the casing member 1 is an opening 1b in which is positioned a lens 1c behind which is positioned the light bulb 56 which is arranged to emit light through the lens 1c forwardly from the front end of my electric drill.

Positioned in adjacent relation with the casing member 1 is the hollow cylindrical casing member 2. Interposed between the end of the casing member 2 and the casing member 1 is the journal member 7 through the central portion of which extends the tool operating shaft 14, as shown best in Fig. 3 of the drawings. The one end of the casing member 2 is connected in the casing member 1 by means of the annular portion 1d which surrounds the end of the casing member 2, all as shown best in Fig. 3 of the drawings. The opposite end of the casing member 2 from the casing member 1 is surrounded by the end of the casing member 3 in which the motor field 43 is mounted, as shown best in Figs. 1, 3 and 4 of the drawings. Interposed between the casing members 2 and 3 is the journal member 8 which provides a bearing at its central portion for the rotor shaft 13, as shown best in Fig. 3 of the drawings.

Secured to the opposite end of the casing member 3 from the casing member 2 is the hollow cylindrical casing member 4. Interposed between one end of this casing member 4 and the casing member 3 is the journal member 9 which forms the bearing for the rotor shaft 13 at the opposite end of the rotor from the journal member 8. Secured to the opposite end of the casing member 4 from the casing member 3 and surrounding the same is the casing member 5, as shown best in Fig. 4 of the drawings.

Positioned at the opposite end of the casing member 4 from the journal member 9 is the journal member 10. This journal member 10 provides a bearing at its central portion for the outer side of the rotor shaft 13 and also forms a support for the pump 32, as shown best in Fig. 4 of the drawings. This journal member 10 also provides a bearing for the gear shaft 25 at its one end, as shown best in Fig. 4 of the drawings.

The journal member 11 is secured on the lower inner side of the casing member 5 and is arranged to provide a bearing for the feed screw 15, all as shown best in Fig. 4 of the drawings. 5 This journal member 11 also provides a support for the gear 22 as shown in Fig. 6.

The casing member 5 is provided with an upwardly extending hollow portion 5a arranged to contain and support the main control levers 54 and 55 together with their operating mechanism. This casing member 5 is also curved at its rear portion and secured thereon is the curved casing member 6 which forms the rear end of my electric drill, all as shown best in Fig. 4 of the drawings.

The rotor 12 is a conventional electric motor armature and is arranged to revolve and turn the rotor shaft 13 which is a hollow cylindrical shaft journalled in the journal members 10, 9 and 8, as shown best in Figs. 3 and 4 of the drawings.

The rotor shaft 13 is provided with an eccentric cam portion 13a thereon, as shown best in Fig. 4 of the drawings. This eccentric cam portion 13a is arranged to operate the pump 32,

25 which is a substantially conventional cam operated cylinder pump. Fixed on one end of this rotor shaft 13 is the gear 24 which is in meshed relation with the gear 23 on the gear shaft 25. As shown in Fig. 3 of the drawings the rotor shaft 30 13 is provided with inwardly and outwardly extending key portions 13b and 13c. These key portions 13b and 13c are shown in cross section in Fig. 7 of the drawings. The key portion 13b is arranged to engage the hammer members 44 and 45 and the inwardly extending key portion 13c is arranged to engage a slotted portion 14a in the upper side of the tool operating shaft 14, as shown in Figs. 3 and 7 of the drawings.

The tool operating shaft 14 is reciprocally mounted in the rotor shaft 13 and is guided therein by the key portion 13c, as hereinbefore described. This tool operating shaft 14 at its end portion 14b, which extends outwardly of the end of my electric drill is arranged to support a conventional drill steel retaining chuck, not shown in the drawings and which is no part of my present invention. This tool operating shaft 14 is also provided with an annular groove portion 14c in which is positioned the slip ring 53. Secured

50 to this slip ring 53 by means of the sleeve 53a is the tool operating shaft cover 52. This tool operating shaft cover 52 is preferably made of leather, or other suitable material and is arranged in the form of bellows and is secured at its inner end to the journal member 7, all as shown best in Fig. 3 of the drawings. This tool operating shaft cover 52 provides a cover for the tool operating shaft 14 at the portion thereof extending outwardly from my electric drill at the front end thereof. The tool operating shaft 60 14 on its outer side is provided with annular groove portions 14d. These annular groove portions 14d are angular in cross section and diverge toward the rear end of my electric drill. These annular groove portions 14d are arranged to be engaged by the teeth 48a of the tool operating shaft clutch 48, as shown best in Fig. 3 of the drawings. Near the end portion 14b of this tool operating shaft 14 and centrally thereof is an opening 14e. This opening 14e is arranged to conduct air or water outwardly to the drill steel or other tool used in connection with the drill operating shaft 14. This tool operating shaft 14 is provided with an enlarged bore 14f communicating with the opening 14e, as shown best in

Fig. 3 of the drawings. Reciprocally and revolvably mounted in this enlarged bore 14f of the tool operating shaft 14 is the feed screw 15. This feed screw 15 is arranged in screw threaded engaged relation with the feed screw engaging nut 16. This feed screw engaging nut 16 is positioned in an enlarged bore portion 14g of the tool operating shaft 14 near the rear end thereof, as shown best in Figs. 4 and 6 of the drawings. This feed screw engaging nut 16 is reciprocally mounted in the enlarged bore portions 14g of the tool operating shaft 14 and is keyed in the tool operating shaft 14 by means of the key portion 16a, all as shown best in Fig. 6 of the drawings. Engaging opposite sides of the feed screw engaging nut 16 are coil compression springs which are held in place by means of the nut 14h screw threaded in the rear end of the tool operating shaft 14. The feed screw 15 is a conventionally formed helical screw and is provided with a central bore 15a therein arranged to conduct air or water, as shown best in Figs. 3 and 4 of the drawings. Positioned on the forward end of this feed screw 15 is a packing groove portion 15b which engages the enlarged bore 14f of the tool operating shaft 14, as shown best in Fig. 3 of the drawings.

Secured on this feed screw 15 in fixed relation therewith adjacent the gear 24 is the gear 18. Secured in fixed relation with the feed screw 15 on the opposite side of the journal member 11 from the gear 18 is the gear 19. Secured on the extending end of the feed screw 15 adjacent the gear 19 is the feed screw swivel connection 17, which is a conventional liquid conducting swivel connection member arranged to conduct liquid from the pump outlet conductor 34 to the internal bore 15a of the feed screw 15, all as shown best in Fig. 4 of the drawings.

The gear 20 is freely revolvably mounted on the gear shaft 25 and is in meshed relation with the gear 22 supported by the journal member 11 as shown best in Figs. 4 and 6 of the drawings. The gear 21 is freely revolvably mounted on the gear shaft 25 and is in meshed relation with the gear 18, as shown best in Fig. 4 of the drawings.

The gear 23 is fixed on the gear shaft 25 and is arranged in meshed relation with the gear 24 on the rotor shaft 13. The gear shaft 25 is revolvably mounted in the journal member 10 at its one end and is journaled in the casing member 5 at its other end, all as shown best in Fig. 4 of the drawings.

The clutch member 26 is secured to the gear 20 and is arranged to engage the clutch member 27 which is fixed on the gear shaft 25.

The clutch member 28 is arranged in fixed relation with the gear 21 and is arranged to engage the clutch member 29. This clutch member 29 is in fixed relation with the gear 23 and the gear shaft 25. It will be here noted that I have positioned compression springs between the clutch members 26 and 27 and between the clutch members 28 and 29 so that the clutch members 26 and 27 cannot be engaged at the same time the clutch members 28 and 29 are engaged.

The clutch operating trip lever 30 is arranged to engage one side of the gear 18 in opposed relation to the clutch operating trip lever 31, as shown best in Fig. 4 of the drawings. The clutch operating trip lever 30 is pivotally mounted on a bolt 30a and is arranged to engage the clutch member 27 for shifting the same away from the clutch member 26 when the feed screw 15 has forced the tool operating shaft 14 inwardly to

the limits of its travel relatively with the key portion 13c of the rotor shaft 13 in engagement with the slotted portion 14a of said tool operating shaft.

The clutch operating trip lever 31 is arranged to engage the opposite side of the gear 18 from the clutch operating trip lever 30 and is arranged to force the clutch member 28 out of engagement with the clutch member 29 when the feed screw 15 has shifted the tool operating shaft 14 outwardly to the limits of its travel relatively with the key portion 13c of the rotor shaft 13 in the slotted portion 14a of said tool operating shaft 14, all as shown best in Figs. 3 and 4 of the drawings. This clutch operating trip lever 31 is journalled on the bolt 30a and is integral with the clutch operating lever 30, as shown best in Figs. 4 and 6 of the drawings. The upper end of this clutch operating trip lever 31 is arranged to engage the side of the gear 21 for shifting the clutch member 28 out of engagement with the clutch member 29, as indicated by dash lines in Fig. 4 of the drawings. The bolt 30a is supported in connection with the lower side of the casing 5, all as shown best in Fig. 4 of the drawings.

The pump 32, as hereinbefore described, is operated by an eccentric cam portion 13a on the rotor shaft 13 and this pump 32 is a substantially conventional cylinder pump having a substantially manifold shaped tubular pump inlet conductor 33 communicating with the pump inlet valve 35, as shown best in Fig. 4 of the drawings. This pump 32 is also provided with a pump outlet conductor 34 which is of hollow tubular material and substantially the form of a manifold, as shown best in Fig. 4 of the drawings. Communicating with this pump outlet conductor 34 is a tubular member 34a extending to the feed screw swivel connection member 17 and communicating therewith for feeding liquid or air from the pump 32 into the internal bore 15a of the feed screw 15.

The pump inlet valve 35 is a two-way valve and is provided with a water inlet conductor 38 and an air inlet conductor 39. Intermediate the air inlet conductor 39 and the valve 35 is a small air cleaner 40. This air cleaner is substantially conventional in form and function. The pump inlet valve 35 is provided with an operating lever 35a connected with which is the valve operating link 37 which extends to the upper side of the casing 4 of my electric drill. Pivotally mounted on the upper side of the casing 4 is the valve operating lever 36 with which is connected the valve operating link 37, all as shown best in Fig. 4 of the drawings.

The fan 41 is fixed on the outer side of the rotor shaft 13 intermediate the journal member 9 and the pump 32, as shown best in Fig. 4 of the drawings. This fan 41 is arranged to provide a circulation of air through the openings 9a in the journal member 9 around the rotor 12 for cooling the motor of my electric drill. This fan 41 also circulates air around the pump 32 for cooling the same.

The casing 4 is provided with air circulation openings 4a therein, as shown best in Fig. 4 of the drawings. Which openings 4a are positioned outwardly of the pump 32. The casing 3 is provided with openings 3a therein at the opposite end thereof from the fan 41, as shown best in Figs. 1 and 3 of the drawings. The armature brushes 42, as shown best in Figs. 1 and 4 of the drawings, are conventional electric motor armature brushes and these armature brushes 42 are

secured on the journal member 9, as shown best in Fig. 4 of the drawings.

The motor field 43 is secured on the inner side of the casing member 3 in concentric relation around the rotor 12, as shown best in Figs. 1, 3 and 4 of the drawings.

The hammer member 44 is reciprocally mounted on the rotor shaft 13 forwardly of the journal member 8 and is guided by the key portion 13b which extends into the hammer 44, as shown best in Fig. 7 of the drawings. This hammer member 44 is circular in cross section, as shown in Fig. 7 of the drawings, and connected therewith is a roller bearing 44a. This roller bearing 44a engages a recessed track portion 27a in the cam member 47, as shown best in Figs. 3, 8 and 9 of the drawings. Referring particularly to Figs. 8 and 9 of the drawings, it will be observed that the roller bearing 44a in the recess track portion 47a of the cam member 47 forces the hammer member 44 backwardly against the compression spring 46 due to the angular helical relation of the recess track portion 47a in the cam member 47. When the roller bearing 44a reaches the abrupt turn 47b of the recess track portion 47a, the hammer member 44 is instantly pressed forwardly toward the hammer member 45 by the hammer operating spring 46. It will therefore be understood that each time the rotor shaft 13 revolves, the hammer member 44 reciprocates backwardly and forwardly on the rotor shaft 13 guided thereon by the key portion 13b. The hammer member 45 is arranged to be struck by the hammer member 44 with each revolution of the rotor shaft 13. This hammer member 45 is reciprocally mounted on the rotor shaft 13 and guided thereon by means of the key portion 13b. Secured to this hammer member 45 is the tool operating shaft clutch 48. This tool operating shaft clutch 48, in connection with the hammer member 45, is maintained in rearwardly compressed relation toward the hammer member 44 by means of the spring 45a.

The tool operating shaft clutch 48 is provided with inwardly extending teeth 48a which are arranged to engage the annular grooves 14d of the spool operating shaft 14, as shown best in Fig. 3 of the drawings. The outer ends of these teeth 48a are pivotally mounted in connection with curved levers 48b. These curved levers 48b are stationarily pivoted in connection with the tool operating shaft clutch 48 by means of the pins 48c.

Interposed between the extending ends of the levers 48b and the tool operating shaft clutch 48 are compression springs 48d. These compression springs 48d tend to force the extending ends of the levers 48b outwardly from the tool operating shaft clutch 48 maintaining certain engaged relation of the teeth 48a with the groove portions 14d in the outer side of the tool operating shaft 14, all as shown best in Fig. 3 of the drawings.

The clutch control ring 51 is positioned in surrounding relation with the curved levers 48b of the tool operating shaft clutch 48, and this clutch control ring 51 is connected with the clutch operating lever 49, as shown best in Figs. 1, 2 and 3 of the drawings. This clutch operating lever 49 is pivotally mounted on a bolt 49a in rigid connected relation with the casing 2, as shown best in Figs. 2 and 3 of the drawings.

Pivotedly connected with the extending ends of the clutch operating lever 49 is the clutch control link 50, as shown best in Figs. 1, 3 and 4 of the drawings. The clutch control link 50 extends backwardly from the clutch operating lever 49

through the journal member 8, the motor field 43 and the journal members 9 and 10 and this clutch control link 50 is arranged to be engaged by the main control lever 54 at its opposite end 5 from the clutch operating lever 49, as shown best in Fig. 4 of the drawings.

The main control lever 54 is arranged in pivoted relation with the casing 5 and is pivotally supported on a bracket 54a below the upper side 10 of the casing 5, as shown best in Fig. 4 of the drawings. The lower end of this control lever 54 is arranged to engage the gear 21 at its one side and the clutch member 27 at its other side for shifting the clutch member 28 into engagement 15 with the clutch member 29 and the clutch member 27 into engagement with the clutch member 26 respectively. This main control lever 54 is also arranged to force the clutch control link 50 backwardly for pivoting the clutch operating 20 lever 49 and shifting the clutch control ring 51 over the curved portion of the levers 48b for pivoting the same and releasing the teeth 48a from the annular groove portions 14d of the tool operating shaft 14. The main control lever 55 is provided with a cam portion on its lower end and is 25 arranged to shift the latch member 55a into engagement with the clutch control link 50 for latching the same in position when shifted backwardly by the main control lever 54. The main 30 control levers 54 and 55 are provided with detent members 55a which are arranged to engage recessed portions 55c in the casing member 5 for holding said main control levers 54 and 55 in certain positions for controlling the operating mechanism of my electric drill.

The operation of my electric drill is substantially as follows: When it is desired to use my electric drill for drilling holes in rocks or other substances, a conventional drill steel is arranged 40 in connection with a chuck on the end of the tool operating shaft 14. Said chuck is not shown in the drawings and is no part of my present invention. The operator starts my electric drill by operating a switch handle 57 on the upper side of the casing 3 of my electric drill. When the electric switch 57 is operated, the rotor 12 revolves inside the motor field 43 carrying with it the rotor shaft 13 revolving the eccentric cam 13a and operating the pump 32. At the same time 45 the hammer member 44 is reciprocated on the rotor shaft 13 by means of the cam 47, as hereinbefore described. The hammer member 44 strikes the hammer member 45 which is connected with the tool operating shaft clutch 48. The teeth 48a in engagement with the groove portions 14d of the tool operating shaft 14 force the tool operating shaft 14 outwardly with each operation of the hammer member 44. It will be here noted that the key portion 13c of the rotor shaft 13 in connection with the slotted portions 14a of the tool operating shaft 14 revolves the tool operating shaft 14 in conforming relation with the rotor shaft 13. The tool operating shaft clutch 48 revolves with the hammer member 45 50 on the rotor shaft 13 and the compression springs 48d force the teeth 48a into certain engaged relation with the annular groove portion 14b of the tool operating shaft 14. The compression spring 45a is arranged to force the hammer member 45, together with the tool operating shaft clutch 48, toward the hammer member 44 as it passes toward the rotor 12 with each revolution thereof, advancing the teeth 48a from one of the grooves 55 14d to the next groove 14d in the tool operating

shaft 14 as said tool operating shaft 14 feeds outwardly from my electric drill.

As shown in Fig. 4 of the drawings, the gear 24 on the rotor shaft 13 is in mesh with the gear 23 fixed on the gear shaft 25. The gear 21 revolves in corresponding direction with the gear 23 when the clutch members 28 and 29 are engaged. This gear 21 in mesh with the gear 18 revolves the gear 18 in a corresponding direction to the gear 24 and the gear ratio between the gear 21 and 18 is so arranged that the gear 18 revolves faster in the same direction than the gear 24. Therefore, the feed screw 15 in connection with the gear 18 revolves slowly within the tool operating shaft 14 in relation with the revolution thereof which conforms to the revolution of the rotor shaft 13.

It will be obvious that as the feed screw 15 revolves faster than the tool operating shaft 14, the feed screw engaging nut 16 operating on the screw threads of the feed screw 15 shifts the tool operating shaft outwardly away from the gear 18 toward the front end of my electric drill. When the tool operating shaft 14 reaches its limit of travel and engages the end of the key portion 13c of the rotor shaft 13, the gear 18 tends to shift backwardly toward the journal member 11 pivoting the clutch operating lever 31 backwardly and forcing the clutch member 28 out of engagement with the clutch member 29 and permitting the gear shaft 25 to revolve freely within the gear 21 which stops the operation of the feed screw 15 and the outward movement of the tool operating shaft 14 in operative relation therewith. When it is desired to retract the tool operating shaft 14, the lever 54 is shifted forwardly at its upper end forcing the clutch member 27 into engagement with the clutch member 26 so that the gear 20 is revolved in mesh relation with the gear 22 operating the gear 19 in mesh with the gear 22 in the opposite direction from the gear 24 on the rotor shaft 14. It will be obvious that the feed screw 15 retracts the tool operating shaft 14 much faster than the tool operating shaft is fed outwardly due to the arrangement of the gears whereby the gear 19 operates in the reverse direction from the gear 24. When the clutch members 27 and 26 are engaged and the gears 20, 22 and 19 are operating the feed screw 15, the tool operating shaft 14 passes backwardly toward the gear 18 and when the tool operating shaft 14 reaches its limit of travel and engages the end of the key portion 13c of the rotor shaft 13, the gear 18 tends to shift toward the gear 24 pivoting the lever 30 and disengaging the clutch member 27 from the clutch member 26 stopping the reverse operation of the feed screw 15 and preventing breakage of the mechanism of my electric drill. It will be here noted that the main control lever 54 is arranged to engage the gear 21 and the clutch 27 at its opposite side for shifting the clutch members 27 and 28 into engagement with the clutch members 26 and 29 respectively.

In connection with the pump inlet conductor 33 is the pump inlet valve 35. This pump inlet valve 35 is controlled by the lever 36 and is arranged to admit either water or air to the pump 32 so that water or air may be conducted through the pump outlet conductor 34 through the conductor 34a and into the hollow bore 15a of the feed screw 15 through the feed screw swivel connection 17. Water or air is forced through the

feed screw 15 and is supplied to the drill steel in connection with my electric drill.

It will be here noted that when the hammer member 44 reciprocally shifts the tool operating shaft 14 in the rotor shaft 13, the springs on opposite sides of the feed screw engaging nut 16 absorb the shock and the feed screw engaging nut 16 shifts longitudinally in the tool operating shaft 14, corresponding with the operation of the hammer member 44.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In an electric drill of the class described, the combination of a casing, an electric motor in said casing, a hollow rotor shaft for said motor, a tool operating shaft reciprocally mounted in said rotor shaft, a feed screw internally of said tool operating shaft and operatively engageable therewith for longitudinally shifting said tool operating shaft in said rotor shaft, said feed screw provided with a central hollow conductor portion and a pump operated on the outer side of said rotor shaft arranged to force substance through said feed screw.

2. In an electric drill of the class described, the combination of a casing, an electric motor in said casing, a hollow rotor shaft for said motor, a tool operating shaft reciprocally mounted in said rotor shaft, a feed screw internally of said tool operating shaft and operatively engageable therewith for longitudinally shifting said tool operating shaft in said rotor shaft, a stationary cam member in said casing and a hammer member operated by said rotor shaft and engageable with said cam member.

3. In an electric drill of the class described, the combination of a casing, an electric motor in said casing, a hollow rotor shaft for said motor, a tool operating shaft reciprocally mounted in said rotor shaft, a feed screw internally of said tool operating shaft and operatively engageable therewith for longitudinally shifting said tool operating shaft in said rotor shaft, a stationary cam member in said casing, a hammer member operated by said rotor shaft and engageable with said cam member, and a tool operating shaft clutch frictionally engageable with said tool operating shaft and engageable with said hammer member.

4. In an electric drill of the class described, the combination of a casing, an electric motor in said casing, a hollow rotor shaft for said motor, a tool operating shaft reciprocally mounted in said rotor shaft, a feed screw internally of said tool operating shaft and operatively engageable therewith for longitudinally shifting said tool operating shaft in said rotor shaft, a stationary cam member in said casing, a hammer member operated by said rotor shaft and engageable with said cam member, and a tool operating shaft clutch frictionally engageable with said tool operating shaft and engageable with said hammer member, said tool operating shaft clutch freely shiftable in one direction relatively with said tool operating shaft.

5. In an electric drill of the class described,

the combination of a casing, an electric motor in said casing, a hollow rotor shaft for said motor, a tool operating shaft reciprocally mounted in said rotor shaft, a feed screw internally of said tool operating shaft and operatively engageable therewith for longitudinally shifting said tool operating shaft in said rotor shaft, a stationary cam member in said casing, a hammer member operated by said rotor shaft and engageable with said cam member, a tool operating shaft clutch frictionally engageable with said tool operating shaft and engageable with said hammer member, said tool operating shaft clutch freely shiftable in one direction relatively with said tool operating shaft, and control lever and link means arranged to release said tool operating shaft clutch from said tool operating shaft.

6. In an electric drill of the class described, the combination of a casing, an electric motor in said casing, a hollow rotor shaft for said motor, a tool operating shaft reciprocally mounted in said rotor shaft, a feed screw internally of said tool operating shaft and operatively engageable therewith for longitudinally shifting said tool operating shaft in said rotor shaft, said tool operating shaft extending outwardly from said casing, and a retractable cover for said tool operating shaft at its outwardly extending portion.

7. In an electric drill of the class described, the combination of a casing, an electric motor in said casing, a hollow rotor shaft for said motor, a tool operating shaft reciprocally mounted in said rotor shaft, a feed screw internally of said tool operating shaft and operatively engageable therewith for longitudinally shifting said tool operating shaft in said rotor shaft, means for holding and guiding said tool operating shaft in conforming revolute relation therewith, cooperative gear means in connection with said rotor shaft and said feed screw and clutch means in connection with said cooperative gear means for reversing the revolute operation of said feed screw, and trip means in operative relation with said gear means for automatically disengaging said clutch means.

8. In an electric drill of the class described, the combination of a casing, an electric motor revolvably mounted in said casing, a hollow rotor shaft for said motor, a tool operating shaft reciprocally mounted in said hollow rotor shaft, a hollow feed screw positioned in said tool operating shaft arranged to longitudinally shift said tool operating shaft in said hollow rotor shaft and means in said casing for forcing matter through said hollow feed screw.

9. In an electric drill of the class described, the combination of a casing, an electric motor revolvably mounted in said casing, a hollow rotor shaft for said motor, a tool operating shaft reciprocally mounted in said hollow rotor shaft, a hollow feed screw positioned in said tool operating shaft arranged to longitudinally shift said tool operating shaft in said hollow rotor shaft, means in said casing for forcing matter through said hollow feed screw, and gear means operated by said rotor shaft and arranged to reverse said feed screw.

10. In an electric drill of the class described, the combination of a casing, an electric motor revolvably mounted in said casing, a hollow rotor shaft for said motor, a tool operating shaft reciprocally mounted in said hollow rotor shaft, a hollow feed screw positioned in said tool oper-

ating shaft arranged to longitudinally shift said tool operating shaft in said hollow rotor shaft, means in said casing for forcing matter through said hollow feed screw, gear means operated by said rotor shaft and arranged to reverse said feed screw, and clutch means in connection with said gear means arranged to reverse said feed screw.

11. In an electric drill of the class described, the combination of a casing, an electric motor revolvably mounted in said casing, a hollow rotor shaft for said motor, a tool operating shaft reciprocally mounted in said hollow rotor shaft, a hollow feed screw positioned in said tool operating shaft arranged to longitudinally shift said tool operating shaft in said hollow rotor shaft, means in said casing for forcing matter through said hollow feed screw, gear means operated by said rotor shaft and arranged to reverse said feed screw, gear means operated by said rotor shaft and arranged to revolve said feed screw, clutch means in connection with said gear means arranged to reverse said feed screw, and main control levers in connection with said clutch means.

12. In an electric drill of the class described, the combination of a casing, an electric motor revolvably mounted in said casing, a hollow rotor shaft for said motor, a tool operating shaft reciprocally mounted in said hollow rotor shaft, a hollow feed screw positioned in said tool operating shaft arranged to longitudinally shift said tool operating shaft in said hollow rotor shaft, means in said casing for forcing matter through said hollow feed screw, gear means operated by said rotor shaft and arranged to reverse said feed screw, gear means operated by said rotor shaft and arranged to revolve said feed screw, clutch means in connection with said gear means arranged to reverse said feed screw, main control levers in connection with said clutch means, and hammer means in operative relation with said tool operating shaft.

13. In an electric drill of the class described, the combination of a casing, an electric motor revolvably mounted in said casing, a hollow rotor shaft for said motor, a tool operating shaft reciprocally mounted in said hollow rotor shaft, a hollow feed screw positioned in said tool operating shaft arranged to longitudinally shift said tool operating shaft in said hollow rotor shaft, means in said casing for forcing matter through said hollow feed screw, gear means operated by said rotor shaft and arranged to reverse said feed screw, and hammer means in operative relation with said tool operating shaft.

14. In an electric drill of the class described, the combination of a casing, an electric motor revolvably mounted in said casing, a hollow rotor shaft for said motor, a tool operating shaft reciprocally mounted in said hollow rotor shaft, a hollow feed screw positioned in said tool operating shaft arranged to longitudinally shift said tool operating shaft in said hollow rotor shaft, means in said casing for forcing matter through said hollow feed screw, gear means operated by said rotor shaft and arranged to reverse said feed screw, hammer means in operative relation with said tool operating shaft, and a tool operating shaft clutch engaging said tool operating shaft and arranged to receive hammer impulses from said hammer means.
